ADJUSTABLE BRUSH IN A SUCTION
CLEANING TOOLWarren A. Humphrey, Canton, Ohio, assignor to
The Hoover Company, North Canton, Ohio, a
corporation of Ohio

Application September 7, 1946, Serial No. 695,414

2 Claims. (Cl. 15—373)

1

The present invention relates to new and novel improvements in a surface-cleaning tool adapted to be used with suction cleaners.

An object of the invention is to provide a new and improved surface-cleaning tool. Another object is to provide a surface-cleaning tool having a brush which is adjustable to extend below the nozzle mouth inlet and to support the cleaning tool on the surface being cleaned. Other objects and advantages of the invention will be apparent from the following specification and drawings, wherein:

Figure 1 is a sectional view of the cleaning tool, showing the brush in one adjusted position;

Figure 2 is a view similar to Figure 1, but showing the brush in another adjusted position;

Figure 3 is a section along the line 3—3 of Figure 2; and

Figure 4 is a bottom view of the cleaning tool with the brush removed.

The cleaning tool comprises a nozzle body 10 and a brush housing 11. The nozzle body includes front and rear surface-contacting lips 12 and 13, end lips 14—14, a front wall 15, a rear wall 16, top wall 17, opposite end walls 18—18, and a socket 19 adapted to receive one end of an unshown hose, the opposite end of which is connected to a suction cleaner. The nozzle lips define an inlet 20 communicating with a suction air passage 21 connected to the outlet of the socket 19.

The brush housing 11 is arranged rearwardly of the nozzle inlet 20 and is formed by the rear nozzle wall 16, the top wall 17, a rear wall 22, and opposite end walls 23—23, the marginal edge 24 of the latter being spaced upwardly from the lips defining the nozzle inlet 20. Disposed in the brush housing 11 is a brush 25 having a brush back 26 provided with bristles 27. The brush 25 is secured to a spring 28, the opposite ends of which are provided with hooks 29 and 30 which respectively engage shouldered portions 31 and 32 at the opposite ends of the brush back 26, and the spring is attached to the top wall 17 by a pair of rivets 33. The brush 25 is removably inserted in the spring hooks 29 and 30 by inserting the shoulder 32 in the hook 29 and moving the hook 29 by means of a tab 34 to insert the shoulder 31 into the spring hook 29. A pair of spring leaf fingers 60—60 integral with the spring 28 exerts a downward force on the brush back 26, while the spring hooks 29 and 30 exert an upward force on the brush back 26 to normally maintain the brush 25 in the retracted position, shown in Figure 1, so that the brush back 26 is substantially

2

rigid in the brush housing 11 and abuts the exposed ends of the rivets 33.

The brush back 26 is provided along its opposite faces with a recess 35 of irregular contour, each having a portion 36 extending through the vertical height of the brush back, an inclined surface 37, and a horizontal surface 38. Slidably mounted in the recess 35 is a substantially U-shaped adjusting member 39 having each of its depending portions 40—40 provided with a horizontal surface 41 and an inclined surface 42, while the top portion is secured by a screw 44 to a slideable member 45. The depending portions 40 of the adjusting member 39 are received in cut-out portions 46 in the spring 28.

The slideable member 45 is elongated and is provided at its opposite ends with upstanding lugs 47 and 48 and is slidably mounted in a recess 49 disposed between the top wall 17 and the socket 19, and the lugs 47 and 48 are received in complementary recesses 51 and 52, respectively, when the brush has been moved to different adjusted positions. The depending portions 40 of the adjusting member 39 extend through a slot 50 in the top wall 17, and the slideable member 45 closes the slot 50 in all of its adjusted positions.

As shown in Figure 1, when the brush 25 is in its retracted position, the inclined portions 42—42 of the adjusting member 39 are spaced from the inclined surfaces 37—37 in the recess 35 and the horizontal surfaces 41—41 do not abut or bear against any portion of the brush back 26, so that the spring 28 and spring fingers 60 are the sole means for retaining the brush 25 in its rigid retracted position.

In using the cleaning tool with the brush 25 in its retracted position, as shown in Figure 1, so as to be out of engagement with the surface being cleaned, air is drawn through the nozzle inlet 20, air passageway 21, and socket 19 and is conducted by an unshown dusting tool hose to a suitable source of suction-creating means. The operator moves the nozzle lips over the covering to be cleaned to dislodge the embedded dirt, and thereafter the suction-creating means draws the dirt-laden air through the cleaning tool.

When it is desired to vigorously brush a surface, then the slideable member 45 is moved from the position shown in Figure 1 to that shown in Figure 2, and during its movement the inclined surfaces 42 slide along the inclined surfaces 37 of the recess 35 until the horizontal surfaces 41 rest on the horizontal surfaces 38 of the recess 35 to thereby protract the bristles 27 below the

surface of the nozzle lips. In this protracted position of the brush, the flat surfaces 41 of the adjusting member 39 abuts the horizontal surfaces 38 in the recess 35 and the spring 28 exerts an upward force to thereby rigidly adjust the brush in its protracted position. In this adjusted position of the brush, the bristles 27 space the nozzle lips from the surface being cleaned and are the sole support for the cleaning tool; however, the suction air passing through the cleaning tool removes the dirt loosened from the surface being cleaned by the action of the bristles 27.

I claim:

1. A cleaning tool comprising a body, a suction nozzle in said body, a brush adjustably mounted on said body, means for adjusting said brush relative to said body to different positions, said brush adjusting means including a member movable on said body and having spaced manually-operated means for moving said member relative to said body to adjust said brush to its different operating positions, and spaced recesses in said body each adapted to receive one of said manually-operated means when said brush has been moved to one of its adjusted positions with the other of said manually operated means out of its respective recess.

2. In a surface cleaning tool, a body having a suction cleaning nozzle, a surface cleaning brush having a cam surface, resilient means movably supporting said brush on said body and urging

said brush to one adjusted position with respect to said body, adjusting means shaped to receive said resilient means and terminating therebeyond in a cam surface for engagement with said brush cam surface, and means mounting said adjusting means on said body for movement relative to said resilient means to engage said cam surfaces and adjust said brush to another position.
